UNITED STATES PATENT OFFICE.

GEORGE WALTHER, OF DAYTON, OHIO.

PATTERN FOR CASTING STEEL WHEELS.

Application filed June 16, 1921. Serial No. 478,133.

To all whom it may concern:

Be it known that I, GEORGE WALTHER, a citizen of the United States, residing at Dayton, in the county of Montgomery and State of Ohio, have invented certain new and useful Improvements in Patterns for Casting Steel Wheels, of which the following is a specification, reference being had therein to the accompanying drawing.

10 My invention relates to patterns for casting steel wheels and in particular to composite patterns and a method of using such patterns.

The object of the invention is to provide 15 an economical mechanism and method of producing cast steel wheels. It is an object to provide a standard pattern for casting cast steel wheels which will always be used for casting of all wheels despite various 20 other modifications in the different makes of wheels to suit different types of vehicles and different types of axles and bearings. By having a standard pattern to which all supplementary parts may be attached the expense of casting different styles of wheels is 25 very materially reduced and the speed of casting is enhanced.

It is my object to provide supplementary 30 portions to vary the diameter of the hub between spokes to vary the curvature between spokes of the portions that join the inner ends of the spokes to one another and to vary the thickness of the base of the spokes. It is my object to provide a pattern 35 upon which supplementary portions may be mounted in combination with the portions just mentioned to vary the width of the hub portion and the diameter of the hub portions while still maintaining the external 40 diameter of the hub member to facilitate standardization of the hubs.

It is a further object to provide a pattern which may be readily assembled and to which parts of varying sizes may be attached. It is a further object to provide a pattern which will provide for the casting of a wheel that has tie bars positioned about its periphery.

Referring to the drawings:

50 Fig. 1 is a plan view of an assembled pattern;

Fig. 2 is a plan view of the inside of one

of the supplementary inner spoke end portions;

Fig. 3 is a plan view of the master spider 55 with the inner spoke end portions removed;

Fig. 4 is a plan view of the master spider with one of the inner spoke end portions removed and the other in place;

Fig. 5 is a section on the line 4—4 of Fig- 60 ure 4;

Fig. 6 is a section on the line 4^a—4^a of Figure 4;

Fig. 7 is an end elevation of the assembled 65 pattern.

Fig. 8 is a section of the wheel showing the method of assembly of the several portions and their method of attachment.

Fig. 9 is a portion of the pattern in ele- 70 vation showing the detachable hub portions in position.

Referring to the drawings in detail, 1 represents the rim of the master pattern; 2 represents the outer spoke ends of the master pattern that has at its inner end the shoulder 3. Attached to and integral with 75 2 is the inner end of the spoke portion of the master pattern which, in combination with the hub, is generally termed the spider. This inner end of the spoke is designated 4, 80 while the hub portion is designated 5. 4 and 5 are shown in dotted lines in Fig. 1. Mounted upon and encasing 4 and 5 is an inner spoke end portion 6 that is attached by the bolts or screws 7 to the spoke portions 4.

85 6 is detachable so that such inner spoke end portions may be varied in their outside dimensions to vary the diameter of the spokes at their inner ends and the curvature of the portion joining the inner ends of the spokes as will be seen from the dotted lines in Fig. 4.

90 It will be observed that the ends 8 are always positioned in the same location so that no matter what other variations and configurations they may have they will fit the universal spider provided for their support against the shoulder 3 of the outer spoke ends 2.

95 In practice it is customary to mount upon 6 a hub portion 9 that has on the base thereof a tapered shoulder 10 to fit within a cut-away portion 11 having a tapered shoulder 12 on 6. This hub portion is retained by

the bolts 13 which pass through 6 into the hub 5. Cutaway portions 14 on the periphery of the pattern enable webs to be cast on the periphery of the wheel rim in the finished wheel.

It will be observed that the entire pattern is divided on the parting line 15 so that it is composed of two major sections in accordance with the usual custom in building a pattern. In a single complete pattern will, therefore, be a pair of spiders, a pair of inner spoke end portions and a pair of hub portions.

The spider will remain constant in its size while the inner spoke end portions may be varied in their configuration although always conforming to the standard outside dimensions necessary to fit the spider. Likewise the hub portions always conform to the standard outside dimensions to fit the inner spoke end portions while their other dimensions may be varied.

Thus it is possible by using these standard portions of the patterns to greatly economize in the cost of making patterns and to expedite the manufacture of such cast wheels.

Varying combinations of sizes and dimensions may be obtained by varying the inner spoke end portions of the pattern and the hub portions while maintaining certain basic dimensions which are standard for all wheels.

While I have shown and described certain features as constituting my invention, it will be understood that parts have been shown for purposes of illustration only, and that I do not desire to be limited to such details, as obvious modifications will occur to a person skilled in the art.

Having thus fully described my invention, what I claim as new and desire to secure by Letters Patent, is:—

1. In a pattern, a master portion consisting of a rim and outer spoke end portions, an inner spoke end and hub portion, means to support a portion of the pattern to form the outside dimensions of the inner spoke ends and the portions uniting said spoke ends, and means to retain said last mentioned portions upon the master portion.

2. In a pattern, a master portion consisting of a rim and outer spoke end portions, an inner spoke end and hub portion, means to support a portion of the pattern to form the outside dimensions of the inner spoke ends and the portions uniting said spoke ends, means to retain said last mentioned portions upon the master portion, and hub portions to determine the diameter and width of the hub mounted on said last mentioned portions.

3. In a pattern, a master pattern consisting of a rim portion and an outer spoke end portion, an inner spoke end portion with a hub connected to the respective outer spoke

end portions, shoulders at the point of junction of said spoke portions, a cap member adapted to be mounted between said shoulders in engagement therewith to enclose said hub portion and inner spoke ends.

4. In a pattern, a master pattern consisting of a rim portion and an outer spoke end portion, an inner spoke end portion with a hub connected to the respective outer spoke end portions, shoulders at the point of junction of said spoke portions, a cap member adapted to be mounted between said shoulders in engagement therewith to enclose said hub portion and inner spoke ends, and supplementary hub portions mounted thereon with means to retain the master pattern and the supplementary portions together as a unit in their standardized locations.

5. In a pattern, a master pattern having a standardized rim, and outer spoke end portions, inner spoke ends of smaller dimensions than the outer spoke ends and integral therewith, a hub connecting said spoke ends to one another as a master internal supporting portion, cap members having their outside dimensions so laid out that they will fit against the shoulders at the point of junction of the elements of the spokes in the master pattern and encase the inner spoke ends of the master pattern and the hub thereof, the respective portions of the encasing members being flush with the outside dimensions of the master outer spoke end portions, and means to retain the several parts in engagement with one another.

6. In a master pattern, one portion consisting of a rim portion, outer spoke end portions and inner spoke end portions, said outer spoke end portions and rim portions being of a configuration of the wheel to be cast while the inner spoke end portions are joined to one another and are of lesser diameter than the other portion, said portions consisting of one-half of a master pattern; a second half of the master pattern of similar character adapted to be united on its flat surface with the flat surface of the other half of the pattern; a cup-shaped hub portion adapted to embrace one side of one portion having its exterior diameter equal to that of the wheel to be cast, a second cup-shaped portion having its marginal edges adapted to engage the marginal edges of the first mentioned portion and encasing its half of the master pattern with it; and means to lock the several portions to one another to form the complete master pattern.

7. In a master pattern, one portion consisting of a rim portion, outer spoke end portions and inner spoke end portions, said outer spoke end portions and rim portions being of a configuration of the wheel to be cast while the inner spoke end portions are joined to one another and are of lesser diameter than the other portion, said portions

consisting of one-half of a master pattern; a second half of a master pattern of similar character adapted to be united on its flat surface with the flat surface of the other half of the pattern; a cup-shaped hub portion adapted to embrace one side of the master pattern having its exterior diameter equal to that of the wheel to be cast, a second cup-shaped portion having its marginal edges

adapted to engage the marginal edges of the first mentioned portion and encasing its half of the master pattern with it; a cut-away portion on each of said cup-shaped portions and hub portions mounted on each of said cup portions, and means to lock the several portions to one another.

In testimony whereof I affix my signature.
GEORGE WALThER.
